TWO-WAY SAFETY RAZOR

Carl D. Fisher, Bentonville, Ark.

Application December 4, 1942, Serial No. 467,877

5 Claims. (Cl. 30—69)

This invention relates to improvements in safety razors of the Gillette style, and more particularly has for its object to provide a safety razor capable of interchangeable use with blades of either the flexible or Gillette type, commonly known as "double-edge blades," or the semi-rigid or Ever-Ready type, commonly known as "single-edge blades."

Another object of my invention is to provide a two-way safety razor of the above character which can be rapidly and cheaply produced by a simple alteration of the Gillette style razor and with a saving of material.

Other objects and advantages will be apparent from the following detailed description of a preferred embodiment of the invention, reference being had to the annexed drawing in which:

Figure 1 is an end view of a safety razor of the Gillette style modified according to the invention and showing a flexible, double-edge type blade associated therewith;

Figure 2 is a view similar to Fig. 1 but showing a semi-rigid, single-edge type blade assembled with the razor;

Figure 3 is a longitudinal cross-sectional view taken through the head and part of the handle of the razor on the line 3—3 of Fig. 2;

Figure 4 is an enlarged perspective view of the cap constituting part of the head; and

Figure 5 is a fragmentary view of an end of the razor corresponding to Fig. 2, but showing an alternative arrangement of the blade-locating lugs.

In the drawing is shown the head end of a safety razor corresponding generally to the well-known Gillette style, but modified in accordance with my invention. The holder comprises a handle 1 and a head 2, the latter being made up of two separable elements, namely a guard 3 of generally rectangular outline and a cap 4 adapted to overlie and cover the major portion of the guard. The cap and guard are transversely curved and the longitudinal edges of the cap lie inwardly of the corresponding edges of the guard. A screw-threaded stud 5 is secured to the concave face of the cap and is adapted to freely pass through a centrally disposed opening in the guard and screw into a socket 1a provided in an end of the handle 1. Thus, when the handle is rotated on the stud the cap is drawn into clamping engagement with the guard. Pins 5a on the cap are arranged to enter complementary recesses in the guard to prevent relative rotation between the parts.

The rectangular blades of the double-edge

type marketed for use with this style of holder are made of relatively thin flexible steel sharpened along both longitudinal edges and provided with openings for passing the stud 5 and pins 5a on the cap. When such a blade G is clamped between the concave face of the cap and the convex face of the guard, as shown in Fig. 1, it is flexed transversely and tension imparted thereto. Safety razors and blades of the style described above are in common use by the public and require no detailed description.

Another style of safety razor which enjoys a wide popularity is that known as the Ever-Ready razor. The Ever-Ready razor differs from the

Gillette razor most importantly in the fact that it is specifically designed to employ a blade in substantially flat unflexed condition. This blade is ordinarily made of semi-rigid, thicker gage metal than the double-edge blade and is not intended or designed to withstand an appreciable amount of transverse bending, as in the case of the double-edge blade. Blades of this semi-rigid type are ordinarily sharpened along only one longitudinal edge and like the double-edge blades are somewhat shorter in length than the cap 4. Notches are formed in the end edges to engage blade-locating lugs on the razor head.

It is a purpose of my invention to provide a modification of the Gillette style of razor described above so as to permit the razor to accommodate blades of the semi-rigid, single-edge type as well as the blades of the flexible, double-edge type. To this end I provide the cap 4 with an elongated slot 6 disposed parallel to one of the straight longitudinal edges of the cap. The slot is located below the point at which the stud joins the cap and, as best shown in Fig. 3, its longitudinal walls slope downwardly from the outer toward the inner face of the cap.

The size of the slot is such as to allow a blade E of the semi-rigid, single-edge type to be introduced therein with its cutting edge extending down between the cap and the guard when the latter parts are in released position. The sloping walls of the slot also determine the angular position of the blade with reference to the face, which position is substantially the same as that which the blade assumes in the Ever-Ready style of holder. The slot may be widened intermediate its ends, as best shown in Fig. 4, to facilitate cleaning soap therefrom after using the razor. This results in a pair of shoulders 6a located at opposite extremities of the slot which exert clamping pressure against the blade when the handle is tightened on the stud 5.

For convenience in locating the cutting edge of the blade **E** in effective shaving position, a pair of lugs **8** are provided on the cap adjacent the ends of the slot, these lugs being so arranged as to fit into the notches formed in the end edges of the blade. Or, alternatively, the lugs **8** may be provided on the blade-engaging face of the guard to abut the corners of the shaving edge of the blade, as illustrated in Fig. 5.

The razor just described is capable of use in the usual manner for clamping double-edge type blades in flexed condition between the curved faces of the cap and the guard in a manner that has already been explained and which is in accordance with conventional practice. When a blade of the semi-rigid, single-edge type is to be used with the holder, the handle **1** is unscrewed from the stud **5** to allow sufficient clearance between the cap **2** and guard **3** to permit the flat blade **E** to be slipped through the slot **6** until it comes to rest against the locating lugs **8**. The handle is then screwed up tight on the stud to clamp the lower edge of the blade between the cap and guard. This imparts a slight tension to the blade and holds it firmly in proper shaving position. After shaving the handle is unscrewed to release the blade, which latter may then be readily withdrawn from the slot.

While I have shown and described my invention with reference to a Gillette style of razor of conventional construction, this is merely by way of example and manifestly various changes in construction and design may be made without departing from the spirit of my invention as defined by the following claims.

I claim:

1. The combination with a safety razor of the style comprising a cap and a guard having opposed, transversely-curved blade-engaging faces, a handle supporting said cap and guard and means for drawing said cap and guard into clamping engagement with a blade, of an elongated slot in said cap disposed parallel to a longitudinal edge of the cap, said slot being so constructed and arranged as to receive the lower portion of a blade of the semi-rigid type and retain it in substantially flat, clamped, shaving position between the cap and the guard.

2. The combination with a safety razor of the style comprising a cap and a guard having opposed, transversely-curved blade-engaging faces, a handle supporting said cap and guard and means for drawing said cap and guard into

clamping engagement with a blade, of an elongated slot in said cap disposed parallel to a longitudinal edge of the cap, said slot being downwardly inclined from the outer convex to the inner concave face of the cap and being so constructed and arranged as to receive the lower portion of a blade of the semi-rigid type and retain it in substantially flat, clamped, shaving position between the cap and the guard.

3. The combination with a safety razor of the style comprising a cap and a guard having opposed, transversely-curved blade-engaging faces, a handle supporting said cap and guard and means for drawing said cap and guard into clamping engagement with a blade, of an elongated slot in said cap disposed parallel to a longitudinal edge of the cap, said slot being downwardly inclined from the outer convex to the inner concave face of the cap and being so constructed and arranged as to receive the lower portion of a blade of the semi-rigid type and retain it in substantially flat, clamped, shaving position between the cap and the guard, and means for locating the cutting edge of the blade with reference to the adjacent edge of the cap.

4. The combination with a safety razor of the style comprising a cap and a guard having opposed, transversely-curved blade-engaging faces, a handle supporting said cap and guard and means for drawing said cap and guard into clamping engagement with a blade, of an elongated slot in said cap disposed parallel to a longitudinal edge of the cap and being expanded in width intermediate its ends, said slot being downwardly inclined from the outer face of the cap towards its inner face and so constructed and arranged as to receive the lower portion of a blade of the semi-rigid type and retain it in substantially flat, clamped, shaving position between the cap and the guard.

5. The combination with a safety razor of the style comprising a cap and a guard having opposed, transversely-curved blade-engaging faces, a handle supporting said cap and guard and means for drawing said cap and guard into clamping engagement with a blade, of an elongated slot in said cap disposed parallel to a longitudinal edge of the guard, said slot being so constructed and arranged to receive the lower portion of a blade of the semi-rigid type and retain it in substantially flat, clamped, shaving position between the cap and the guard.

CARL D. FISHER.
